CATHODE RAY TUBE

Kurt Engel, Koslin, Germany, assignor to General Electric Company, Schenectady, N. Y.

Application September 9, 1932, Serial No. 632,371
In Germany September 10, 1931

4 Claims. (Cl. 250—27.5)

My invention relates to cathode ray tubes and more particularly to cathode ray oscilloscopes.

It is an object of my invention to improve the means for supporting the deflecting plates in tubes of this kind.

Heretofore the deflecting plates were supported by means of the leads sealed into and traversing the wall of the bulb of the tube. If each deflecting plate is supported by a separate wire, it is very difficult to properly adjust the plates relative to each other. Quite particularly in quantity production it is very difficult to arrange the two pairs of deflecting plates in planes normal with respect to one another and in such manner that all tubes shall have the same characteristic.

According to my invention this drawback is avoided by providing a glass annulus to which the deflecting plates are secured by means of holders to which the leads are electrically connected. Preferably a single annulus is provided to support all deflecting plates, these plates being first secured to the annulus outside of the bulb and the annulus together with the plates being then introduced into the bulb.

In the drawing forming part of this specification, an embodiment of my invention is shown diagrammatically by way of example.

In the drawing

30 Fig. 1 is a front view, partly in section, of a cathode ray tube according to my invention.

Figs. 2 and 3 are sections along the lines A—A and B—B of Fig. 1, respectively, drawn to a larger scale.

35 Fig. 4 is a view of an ordinary cathode ray tube containing my improved deflecting plate structure.

In the drawing, 18 is the bulb of a cathode ray tube or oscilloscope. 1 is an annulus made of 40 glass or some other suitable insulating material. The annulus is here shown as a circular ring, but may be shaped differently if desired. 2, 3, 4, 5 are the deflecting plates secured to holding wires 6, 7, 8, 9, respectively, which are sealed 45 into the glass-annulus 1. By securing the plates to the annulus in this manner it is possible to properly adjust the plates outside of the bulb 18 and to thereafter introduce them together with the annulus into the bulb 18. The annulus is 50 preferably secured within the bulb 18 by connecting the ends of the holding wires 6, 7, 8, 9 to the leads 14, 15, 16, 17 by means of flexible sleeves 10, 11, 12, 13, respectively. The leads are preferably sealed in the projections 19, 20, 21, 22 of 55 the tube wall after the holding wires have been connected to them by means of the sleeves. The flexible sleeves are pushed onto the adjoining ends of the holding wires and the leads and owing to their flexibility make sufficient contact since 60 only voltages and practically no current is trans-

mitted to the plates. As will be seen from Figs. 2 and 3, the ends of the holding wires inside the glass annulus are bent upwardly and downwardly in such manner that the pairs of opposite deflecting plates are arranged above and below the annulus, respectively. If desired, the connection between the leads and the holding wires can be established by means of other suitable connecting members.

In Fig. 4, numeral 23 designates a filamentary cathode while the usual anode and fluorescent screen are identified by the reference characters 24 and 25 respectively. The remaining elements in this figure have the same reference characters as in the other figures.

I wish it to be understood that I do not desire to be limited to the exact details of construction shown and described, for obvious modifications will occur to a person skilled in the art.

I claim:—

1. A cathode ray tube comprising an envelope containing a cathode, an anode and a plurality of electrostatically deflecting members, said members being secured to a body of insulating material, supports between said body and envelope, 85 said cathode and anode being supported independently of said body.

2. A cathode ray tube comprising an envelope containing a cathode, an anode and a plurality of electrostatically deflecting members, said members being secured to and equidistantly spaced about an annulus of glass and means for supporting said annulus within the envelope, said cathode and anode being supported independently of the annulus.

3. A cathode ray tube comprising an envelope containing a cathode, an anode and a plurality of electrostatically deflecting plates, said plates being secured to a body of insulating material, supports between said body and the envelope, 100 each of said supports including a flexible coupling.

4. A cathode ray tube comprising an envelope containing a cathode, an anode and a plurality of pairs of electrostatically deflecting plates arranged normal to one another, said plates being secured to a body of insulating material, metal rods between said body and the envelope, said rods constituting leading-in conductors for the respective plates and each rod including a flexible 105 coupling.

KURT ENGEL.
